EXPANDING GAS IN A PLURALITY OF VORTEX TUBES

Jan J. van Deemter, Amsterdam, Netherlands, assignor to Shell Development Company, New York, N. Y., a corporation of Delaware

Application July 23, 1956, Serial No. 599,635

Claims priority, application Netherlands November 15, 1955

18 Claims. (Cl. 62—5)

This invention relates to separating a gas into relatively warmer and colder fractions by expanding the gas with gyratory motion within a vortex tube. More particularly, the invention is concerned with an improvement involving the transfer of heat between one or both of the gas fractions while in motion within the vortex tube, employing for this purpose an auxiliary, coaxial vortex tube within which gas is simultaneously expanded. Broadly considered, either the inner or the auxiliary vortex tube may be used either to cool or to heat gas in the main tube, according to the desire to produce a useful gaseous effluent which is colder or hotter than the initial gas; since, however, the most usual application of vortex tubes is to generate cold, only the former will be specifically described herein.

The vortex tube, also known as the Ranque tube or Hilsch tube, uses no moving parts and is low in cost. It is described in U. S. Patent No. 1,952,281 to Ranque, and Hilsch drew further attention to it in articles published in *Zeitschrift für Naturforschung*, vol. 1, pp. 208-214 (Wiesbaden, Germany, 1946) and in *Review of Scientific Instruments*, vol. 18, pp. 108-113 (New York, 1947). A bibliography on vortex tubes was published by Curley and MacGee, Jr., in *Refrigeration Engineering*, vol. 59, 1951, pp. 66 and 191-193. As disclosed in these publications, the vortex tube includes a vortex chamber having the shape of a body of revolution, such as a cylinder, an inlet for admitting a feed gas under pressure with a gyratory motion, e. g., one or more inlet pipes situated near one end of the tube and disposed tangentially and in the same circumferential direction, and suitable outlet means for discharging one or both of the gas fractions which are produced within the tube. These fractions are formed respectively as a peripheral stream in contact with the inner surface of the tube wall and as a core (usually solid but possibly annular) rotating coaxially within the peripheral stream, the former being warmer and the latter being colder than the feed gas in the case of an adiabatic arrangement. Both fractions have pressures lower than that of the feed gas but the pressure of the fraction having the higher temperature exceeds that of the other fraction, in accordance with the Ranque effect. This phenomenon of the separation of the gas by expansion within the vortex tube into hot and cold fractions is hereinafter referred to as the heat-separation effect; it results in the heating of at least a part of the outer vortex tube wall, unless it is extraneously cooled.

The dimensions of such tubes may vary within wide limits according to the conditions under which the tube is to operate; suitable dimensions and shapes are readily determined experimentally in accordance with the principles and examples given in the art noted above. Thus, the vortex chamber may have a length of 6-30 diameters, lengths of 10-20 diameters being common, and the inlet may be situated near one end, so that most of the length lies to one side of the inlet; this part of the tube is known as the hot end.

2

Various outlet arrangements are possible, some resulting in the separate discharge of the hot and cold fractions from the vortex chamber and others resulting in re-mixing of these fractions and the discharge of all gas as a single stream. By throttling one or both effluent streams from a tube having separate outlets for the hot and cold gases, e. g., by a throttle valve in one of the outlets, the ratio of the discharged streams and, hence, their temperatures can be varied; typical temperature effects are indicated graphically by Hilsch, op. cit. Regardless of whether the fractions are discharged separately, their separate occurrence within the tube affords a ready means of abstracting heat from or adding heat to one or the other of the fractions by heat exchange with a fluid having a temperature that is the same as or only moderately different from that of the initial gas. Thus, cooling of the hot fraction may be effected by providing cooling vanes on the outside of the tube wall, to dissipate heat to the surrounding air, as suggested in Figures 5 and 6 of German patent to Rotter, No. 858,260. More intensive cooling of the tube wall can be effected by circulating a liquid through a space defined by a jacket surrounding the tube. Because of the elevated temperature of the hot gas fraction it is easy to remove heat from the gas into the atmosphere or cooling liquid and thereby reduce the temperature of the effluent stream, both when the latter stream contains all of the expanded gas and when it consists of only the cold fraction thereof.

In general, cooling of the tube by a gas in the known manner is ineffective to achieve intensive cooling of the vortex tube wall because of the low heat transfer coefficient. Refrigeration of the gas to promote heat transfer is not feasible because it necessitates refrigeration machinery; this, if provided, would usually make it unnecessary to use the vortex tube. An increase in the heat transfer coefficient by placing the cooling gas in rapid motion is also not feasible under previously known conditions, since an insufficiently small increase in heat transfer results unless refrigeration is provided. The converse effects are and limitations occur when one seeks to heat gas in the tube.

It is the object of this invention to provide an improved process and apparatus for changing the temperature of a gas stream wherein a gas is used effectively to transport heat to or from a bounding wall of a main vortex tube within which a gas is expanded to separate it therein into hot and cold fractions by the heat-separation effect.

A further object is to provide an improved process and apparatus employing a main and an auxiliary vortex tubes, wherein the latter is used to cool or heat one of the gas fractions in the main vortex tube. Ancillary thereto, it is an object to provide a process and apparatus wherein the auxiliary vortex tube is temperature-conditioned, e. g., cooled, by a coolant which may be a liquid.

In summary, according to the invention, gas is expanded with gyratory motion simultaneously in two vortex tubes having different diameters and disposed in at least partial overlapping relation, so that there are formed within each tube a pair of coaxially moving gas fractions of different temperatures in accordance with the heat-separation effect, the warmer fraction in the inner tube and the colder fraction in the outer tube being in contact respectively with the inner and outer surfaces of the wall of the inner tube, resulting in a flow of heat from the former to the latter fraction. In this operation the said wall of the inner tube is cooled by the rapidly moving cold gas fraction which is produced in situ on the outer surface thereof; the rapid motion increases the heat transfer coefficient while the reduced temperature further augments the flow of heat.

As applied for the generation of cold wherein heat must be removed from the gas in the main vortex tube,

this tube is on the inside. Production of the cold gas in situ is here especially advantageous in that cold losses by convection or radiation during flow from the point of refrigeration of the coolant to the point of utilization are avoided and the need for thermal insulation on pipes is obviated, because the cold fraction is brought into existence only where it is utilized; and the generation of cold by the heat-separation effect is useful in that it requires no refrigeration machinery with moving parts, only a source of gas under pressure being required. Such a source is frequently available in various plants in the form of effluent streams from units operated at superatmospheric pressure.

The gas expanded in one of the vortex tubes may have been previously partly expanded in the other; or a different gas stream, originating in a common or in different sources, may be charged to each tube. In the former, serial arrangement, one may, for example, pass the cold gas discharged from the main vortex tube through a heat exchanger wherein it is used to cool some warmer medium and then admit it into the auxiliary vortex tube for further expansion.

The cold gas produced in situ in the outer, auxiliary vortex tube may be brought to a still lower temperature by intensively cooling the outer wall of the auxiliary tube, either with a liquid circulated through a jacket or through cooling coils or, when the use of a liquid is impracticable or objectionable, by yet another auxiliary vortex chamber.

Each of the vortex tubes may be selected without restriction from among various types, and the two tubes may be of the same or of different types. For convenience in identification, the following classification of tubes on the basis of the gas outlet arrangements is used herein:

Type A.—In this tube a cold fraction is withdrawn through a central, restricted orifice at the cold end and a hot fraction flows out from the extremity of the hot end, usually through a throttle valve.

Type B.—Such a tube is closed at the cold end, and the hot and cold fractions flow through the hot end as coaxial streams which are discharged either separately or as a single composite mixture from the extremity of the tube. Separate discharge may be effected by means of a special device, the simplest form of which is a tube mounted concentrically within the vortex tube near the extremity; the arrangements shown in Figures 13 and 14 of the aforesaid U. S. patent to Ranque are examples.

Type C.—In this type the tube is closed at the hot end and all the gas escapes through the orifice at the cold end. Here the hot gas fraction, after traversing the hot end as a peripheral stream, moves toward the tube axis and flows in the reverse direction to the cold end.

Vortex tubes of types A and B are described in the above-noted U. S. patent to Ranque, while type C is disclosed in the above-mentioned German patent to Roitter.

It is evident from the foregoing that in apparatus employing two vortex tubes, nine possible arrangements are possible. However, for the case where the generation of cold is the object, it is preferable to employ a tube of type A or type C as the inner, main tube, and a tube of type B as the outer, auxiliary tube.

Certain arrangements are illustrated, by way of examples, in the accompanying drawings forming a part of this specification, wherein:

Figure 1 is a longitudinal sectional view of a vortex tube apparatus according to the invention employing a type A inner tube and a type B outer tube;

Figures 2 and 3 are transverse sectional views taken on the correspondingly numbered section lines of Figure 1; and

Figure 4 is a longitudinal sectional view of a modified vortex tube apparatus employing a type C inner tube and a type B outer tube.

Referring to Figures 1-3 in detail, the apparatus may include an inner main vortex tube 10, the hot end of which may include a divergent section 10a and a cylindrical section 10b; these sections are surrounded by a larger, auxiliary vortex tube 11. These tubes are formed with surfaces of revolution about a common axis. The tube 10 has a tangentially directed inlet nozzle 12 which is advantageously joined to the tube wall by a spiral wall 13, so as to center the resulting gas vortex at the axis of the tube. Similarly, the tube 11 has a tangential inlet nozzle 14 connected to the tube wall by a spiral 15. The tube 10 has a restricted, cold-gas discharge orifice 16 formed in the end wall 17 at the cold end by which the tube is in communication with a pipe 18 leading to a heat exchanger 19. The gas discharged from the heat exchanger flows through the pipe 20 to the nozzle 14. A medium to be cooled flows through the heat exchanger via pipes 21 and 22. The extremity of the hot end of the tube 10 communicates with a hot-gas discharge pipe 23 which may be provided with a throttle valve 24. The tube 11 is closed at its cold end by a wall 25 and at its hot end 11a by a wall 26 which has an annular opening 27.

By way of example, the inner tube 10 may be made of thin-walled material which preferably has good heat-conducting properties and have an internal diameter of 10 mm., and a length of 200 mm., the outer tube 11 may then have an internal diameter of 25 mm. and a length of 250 mm. It will be recognized that when the throttle valve 23 is entirely closed the inner tube becomes a type C-vortex tube.

Example

The apparatus may be operated as follows: Gas, e. g., air at a pressure of 20 atm. abs. and a temperature of 68° F., is admitted to the nozzle 12 and is partially expanded tangentially within the main, inner tube 10. The throttle valve 24 is adjusted so that 20% of the introduced gas escapes from this vortex tube through the pipe 23 in the form of hot gas; the remaining 80% of the gas flows through the orifice 16 into the pipe 18 at a pressure of 4 atm. abs. and a temperature of -4° F. After giving up its cold to the fluid which circulates through the heat exchanger 19 and the pipes 21 and 22, the gas flows through the pipe 20 at a pressure of about 4 atm. abs. and a temperature of 59° F. This gas is expanded tangentially into the auxiliary, outer tube 11 through the nozzle 14, thereby producing a vortex and a separation of the gas into an outer, hot fraction and an inner, cold fraction which are in contact respectively with the inner surface of the tube 11 and the outer surface of the tube 10 and in rapid rotational movement about it. As the latter fraction has a very high velocity, a reasonably high heat transfer coefficient can be realized and it is possible to cool the wall of the inner tube 10 intensely. The hot and cold fractions in the auxiliary tube 11 become commingled toward the extremity of the hot end, where their rotational velocity is diminished considerably. The gas finally leaves the tube 11 through the opening 27 at a pressure of 1 atm. abs. and a temperature of 109° F.

The serial connection of the two vortex tubes shown in Figures 1-3 is of particular advantage when the object is not to reach the lowest possible temperatures, but to extract the largest possible number of calories from the cold gas stream so as to produce a large heat transfer in the heat exchanger 19.

Figure 4 shows another connection and a different construction of the two vortex tubes; reference numbers denote parts corresponding to those denoted in Figures 1-3 by numbers increased by twenty. Again, the inner tube 30 is the main tube and the coaxial, outer tube 31 is the auxiliary tube. The vortex tubes have inlet nozzles 32 and 34, respectively, arranged tangentially with connecting spirals as previously described. Separate gas streams, either from the same or from different sources, are ex-

panded tangentially through these nozzles. In this case the hot end 30a—30b of the main tube is closed by a wall 48, so that the tube is of type C and all gas is discharged through an orifice 36 at the cold end, from which it passes through a pipe 38 to a heat-exchanger 39. Thus, all gas expanded in the inner tube is used for cooling purposes. The gas expanded in the outer tube creates a rapidly moving cold fraction surrounding the hot end of the inner tube, as previously described, and all gas expanded in the outer tube is discharged at the extremity of the hot end through an annular opening 47.

The connection of the two vortex tubes according to Figure 4 is advantageous when the pressure of the initial gas is insufficient to permit successive partial expansion in the two tubes, or when it is desired to recover the gas at an elevated pressure after flow through the heat exchanger.

Optionally, the outer tube may have the enclosing wall thereof cooled intensively. Such an arrangement is indicated in Figure 4, wherein a jacket 49 surrounds the tube 31 and is provided with nozzles 50 and 51 for the circulation of a cooling liquid, such as water.

I claim as my invention:

1. Process for changing the temperature of a gas comprising the steps of expanding gas with gyratory motion simultaneously within each of two coaxial vortex tubes of different diameters whereof the tube having the larger diameter surrounds at least a part of the other tube in spaced relation and thereby producing within each of said tubes by the heat-separation effect a pair of coaxially rotating gas fractions of different temperatures, the warmer fraction within the inner tube moving peripherally in contact with the inside of the inner tube wall and the colder fraction within the outer tube moving in contact with the outside of the inner tube wall, and discharging gas from each of said tubes.

2. In a process of producing a cold gas by the heat-separation effect wherein a gas is expanded with a gyratory motion within a vortex tube and cold gas is discharged from the tube, the improvement of cooling the outer wall of said tube by a stream of cold gas which moves rapidly in direct contact with said wall and is produced in situ by the heat-separation effect resulting from the expansion of a gas with gyratory motion within a second vortex tube which at least partially surrounds the first-mentioned tube.

3. Process according to claim 2 wherein said first-mentioned tube has a cold end and a hot end situated respectively on opposite sides of the inlet by which the gas is admitted thereto, said hot end being longer and said cold gas being discharged through an axial orifice at said cold end, and the said rapidly moving stream of cold gas in the second tube is produced by admitting a gas tangentially thereto near the said cold end of the first-mentioned tube, flowing said admitted gas as hot and cold fractions moving helically and coaxially about the first tube along the hot end thereof in a direction away from said inlet, and discharging all said admitted gas from the second tube at the end thereof which is situated in the said direction.

4. Process according to claim 2 wherein the gas which is expanded in the second vortex tube is the cold gas discharged from the first-mentioned tube, said cold gas being flowed in heat exchange with a warmer medium prior to expansion in the second tube.

5. Process according to claim 2, wherein said first-mentioned vortex tube has a cold end and a hot end situated respectively on opposite sides of the inlet by which the gas is admitted thereto, said cold gas is discharged at the said cold end, through an axial orifice with a diameter less than that of the tube, and a separate fraction of hot gas is discharged from said hot end.

6. Process according to claim 2 wherein the confining

wall of the second vortex tube is cooled by applying a cooling medium thereto.

7. Process according to claim 2 wherein said first-mentioned vortex tube has a cold end and a hot end situated respectively on opposite sides of the inlet by which the gas is admitted thereto, and all of the gas admitted to said first-mentioned tube is discharged at the said cold end through an axial orifice of diameter less than that of the tube.

8. Method of producing cold gas in a gas stream which is initially under pressure comprising the steps of expanding said gas in a first vortex tube by admitting the gas thereto tangentially nearer one end than the other and effecting a separation of said gas into a hot fraction moving as a peripheral stream in contact with the inner surface of the tube and a cold fraction rotating coaxially within said peripheral stream; discharging cold gas from said tube; and cooling said hot fraction while within said first tube by similarly expanding gas with gyratory motion a second vortex tube which at least partially surrounds the latter end of the first tube substantially coaxially thereto and thereby producing a second hot fraction moving peripherally within the second tube and a second cold fraction rotating about and in contact with the outer surface of the first vortex tube, thereby cooling the first tube with cold gas which is in rapid motion and is produced in situ, and discharging gas from the second tube.

9. Vortex apparatus for changing the temperature of gas comprising a pair of coaxial vortex tubes of different diameters, the tube of larger diameter surrounding at least a part of the other tube in radially spaced relation; one or more inlets for each said tube disposed for the admission of gas with gyratory motions to produce within each tube a pair of coaxially rotating gas fractions of different temperatures by the heat-separation effect; and discharge means for discharging gas from each of said tubes.

10. Vortex apparatus according to claim 9 wherein the inlet of one of said tubes is connected to a discharge means of the other tube, for the flow of gas successively through said tubes with successive expansions.

11. Vortex apparatus according to claim 10 including a heat-exchanger interconnected between the inlet and discharge means recited in said claim.

12. In combination with the vortex apparatus according to claim 9, means for cooling the gas fraction in the tube of larger diameter which moves in contact with the outer wall thereof.

13. Vortex apparatus according to claim 9 wherein said tube of larger diameter has the gas-inlet situated near one end thereof and the discharge means situated near the other end thereof, said one end being closed against the discharge of gas.

14. Vortex apparatus according to claim 9 wherein the inner tube has a cold end and a hot end situated respectively on opposite sides of the gas-inlet and the discharge means thereof includes wall means at said cold end providing an orifice at the tube axis having a diameter less than that of the tube.

15. Vortex apparatus according to claim 14 wherein said inner vortex tube has a second discharge opening at the end of the hot end for the discharge of hot gas.

16. Vortex apparatus for producing cold gas from a gas stream by the heat-separation effect comprising: a thin-walled tubular body defining a first vortex chamber and having interior and exterior surfaces of revolution, one or more gas-inlets disposed tangentially to said interior surface and dividing said tube into hot and cold ends which are, respectively, relatively longer and shorter and situated on opposite sides of the gas-inlet, and wall means at said cold end providing an axially disposed, cold-gas discharge orifice with a diameter less than that of the tube; a chambered body including a confining wall

which encloses a second, tube-shaped vortex chamber with an interior surface of revolution surrounding said hot end in radially spaced and coaxial relation; one or more gas-inlets disposed tangentially to said inner surface of the second vortex chamber; and means for discharging gas from said second vortex chamber.

17. Vortex apparatus according to claim 16 including means for circulating a cooling fluid about the second vortex chamber near to and in heat exchange relation to said confining wall thereof.

18. Vortex apparatus according to claim 16 including

a heat exchanger having flow passages for the flow of separate gases, one of those passages being connected to receive cold gas from said cold-gas discharge orifice of the first vortex chamber and to discharge gas to the gas-inlet of the second vortex chamber.
